UNITED STATES PATENT OFFICE.

CLARENCE F. BENJAMIN, OF PHILADELPHIA, PENNSYLVANIA.

EXPANSIBLE PULLEY.

No. 896,267.

Specification of Letters Patent.

Patented Aug. 18, 1908.

Application filed March 11, 1908. Serial No. 420,295.

To all whom it may concern:

Be it known that I, CLARENCE F. BENJAMIN, a citizen of the United States, residing at Philadelphia, in the county of Philadelphia and State of Pennsylvania, have invented 5 certain new and useful Improvements in Expansible Pulleys, of which the following is a specification.

This invention relates to expansible pulleys, the object being to provide a pulley which is so constructed that the diameter of the same may be increased or decreased when the same is in operation, so as to increase or diminish the speed.

15 Another object of my invention is to provide very novel means for operating the segmental rim sections of the pulley, so that they will be expanded in succession as they come between the belt, whereby the disadvantages heretofore existing of expanding the pulley in operation is overcome, as the section is expanded when pressure is relieved from the same.

Another object of my invention is to provide 25 very novel means for operating the sections, so that when expanded they will be held rigidly, so as to resist the pressure of the belt.

Another object of my invention is to provide 30 very novel means for locking the sections in their adjusted positions.

A further object of my invention is to connect 35 springs to the arms carrying the segments so that when the operating means is thrown out of engagement with the same, the arms will be drawn inwardly.

A still further object of my invention is to provide operating means which is automatic in operation, and so arranged in respect to 40 the pulley, that the sections will be forced outwardly at the right time, and after all the sections have been forced outwardly, the locking means will be thrown into engagement with the operating wedges, so as to lock 45 them in their adjusted positions.

These objects are attained by the novel arrangement and construction of parts hereinafter fully described and shown in the accompanying drawings, in which:—

50 Figure 1, is a side elevational view of my improved pulley partly broken away to show the operating means. Fig. 2, is a section taken on line 2—2 of Fig. 1. Fig. 3, is a section taken on line 3—3 of Fig. 1. Fig. 55 4, is a perspective view of one of the arms

detached, and, Fig. 5, is a perspective view of one of the wedges.

In the drawings A indicates a shaft on which is fixed a wheel B having a flat inner face provided with radial grooves B' having dovetail shape in section adapted to receive the dovetail bases C', of a series of arms C. Attached to the outer ends of the arms C are plates D, which carry segmental rim sections E forming the periphery of the pulley. Each plate D is secured to the rim section by a screw E' which extends into a central boss D' formed on the plate. This holds the sections rigidly together. The inner ends of the arms C, are on an incline or angled to the side edges, and the ends of the arms are beveled as at C², and thus adapted to fit in the V-shaped grooves F' formed in the inclined faces of the expanding wedges F'. These expanding wedges are shown separately in Fig. 5. They are mounted radially to the shaft A and, at their pointed ends, extend through openings in the wheel B. At their outer ends they are provided with projecting shanks F², which enter 80 within a sleeve G surrounding the same. This sleeve is provided with interior longitudinal radial grooves to receive the shanks, each groove communicating with a radial notch G' formed in one end of the sleeve, 85 and adapted to fit over the wedges F, as will be hereinafter fully described.

The inner edges of the wedges are concaved so as to fit snugly around the shaft, and the ends of the shanks F², are provided 90 with dovetail shaped tongues F³, over which are secured dovetail grooved curved plates H, having beveled faces H', which are adapted to be engaged by a roller I, mounted in a hub K, which is loosely mounted on the 95 shaft A.

Curved plates L, are countersunk in the rim of the wheel B, over the ends of the grooves, and are provided with inwardly projecting portions which fit in the grooves 100 and form stops for the arms C. Secured to the face of the wheel B, are screws M, to which are connected coil springs M', the free ends of which are connected to the arms C, for returning the sections after they have 105 been expanded.

The sleeve G, is provided with an exterior annular groove in which is loosely mounted a sectional sleeve N, provided with oppositely disposed pins N', carrying anti-friction 110

rollers, over which the bifurcated ends of a forked arm O, are adapted to fit, which is carried by an operating bell-crank lever O', pivotally mounted on a stud pin O², which is secured to a suitable support (not shown).

Pivots mounted on the operating lever O', is a forked arm P, the ends of which are bifurcated as shown at P', between which the oppositely disposed pins Q, extend, 13 which are carried by the hub K, the pins being provided with anti-friction rollers. Fixed to the arm P, is an arm R, which extends parallel to the operating lever O', and is connected to the bifurcated end of an 15 operating rod S, through which the operating lever O', extends. The operating rod S, is provided with a spring actuated plunger S', which engages the operating lever, so that when the rod S, is operated, the arm will be 20 swung on its pivot, so as to bring the roller into engagement with the inclined faces of the grooved plates H. This roller is so located that as the respective rim sections are brought around into the space between 25 the return portions of the belt, they will be expanded, and it will be seen that the sections are expanded when pressure is relieved from the same. After the sections are all forced out into an expanded position, the 30 arm O, will force the sleeve G forwardly, so as to lock the wedges in their adjusted position.

The operation of the device is as follows:— Supposing the pulley to be in a closed position, and it is desired to expand the same, the rod S, is forced upwardly which will operate the bell-crank lever R, P, and the sleeve K. The forward movement of the sleeve K thus brings the roller I successively 35 into engagement with the beveled faces of the curved plates carried by the shanks of the wedges, so that the segmental rim sections will be forced successively outward, one at a time, as they come to the space 40 between the belt. As further pressure is applied on the operating rod S, the arm O, will move the sleeve G, forward, so as to bring the notches G' of the same over the wedges F, which will securely lock the segmental sections in their adjusted position. 45 It will be seen as the wedges are forced forwardly they contact with the edges of the segment arms and move the segmental sections outward, thus increasing the diameter of the pulley. It will also be seen that by controlling the movement of the operating rod S, the diameter of the pulley can be 50 regulated. By simply pulling on the operating rod the diameter of the pulley can be decreased as the sleeve G, will be brought 55 into engagement with the curved plates of the shanks of the wedges, so as to bring the wedges back into their normal position, and the springs will return the arms carrying the 60 segmental rim sections.

From the foregoing description it will be seen that I have provided an expansible pulley which is constructed of a very few parts which are so arranged and connected together that they are not likely to get out 70 of order in operation.

Having thus described my invention what I claim as new and desire to secure by Letters Patent is:—

1. In an expansible pulley, a series of radial arms carrying segmental rim sections, and means for forcing out said rim sections successively, and for holding them so forced out. 75

2. In an expansible pulley, a series of radial arms carrying segmental rim sections, a series of wedges contacting with and acting to force out each arm, and a roller adapted to be moved towards the butt ends of said wedges, and to contact successively with 85 them to force said wedges and the arms outward.

3. The combination with a wheel, of arms slidably mounted in the face of said wheel, wedges engaging said arms and means for 90 operating said wedges in succession.

4. In an expansible pulley the combination with a wheel provided with a grooved face, of spring actuated arms mounted in said grooves carrying segmental rim sections, 95 wedges engaging said arms, means for operating said wedges successively, and means for locking said wedges after they have been operated.

5. The combination with a wheel provided 100 with grooves in its face crossing each other at right angles, of arms mounted in said grooves carrying segmental rim sections, wedges engaging the inner ends of said arms, means for operating said wedges in succession, and 105 means for locking said wedges.

6. The combination with a wheel having dovetail grooves formed in its face, of spring actuated arms provided with dovetail heads mounted in said grooves having angled inner 110 ends, segmental rim sections connected to the outer ends of said arms, wedges engaging the inner ends of said arms, means for operating said wedges in succession, and a notched sleeve for locking said wedges. 115

7. The combination with a wheel provided with a radially grooved face, of spring actuated arms mounted in said grooves having angled inner ends, segmental rim sections secured to the outer ends of said arms, 120 wedges engaging the angled ends of said arms provided with shanks carrying plates having beveled faces, and a roller adapted to engage said plates, for the purpose described.

8. The combination with a shaft and a 125 wheel carried thereon having radial grooves in its face, of spring retracted arms mounted in said grooves carrying segmental rim sections, wedges for engaging said arms provided with shanks, means for forcing said wedges 130

against the rim carrying arms, a locking sleeve surrounding the shanks of the wedges, and means for operating said wedges and sleeve.

5 9. In an expandible pulley, the combination with a wheel provided with slidably mounted arms, of segmental rim sections carried by said arms, wedges for operating said arms, means for operating said wedges, 10 and a sleeve for locking and releasing said wedges.

10. The combination with a shaft, and a wheel fixed thereon, of spring retracted arms slidably mounted on the face of said wheel, 15 segmental rim sections carried by said arms, wedges engaging said arms provided with shanks, a sleeve surrounding said shanks provided with notches adapted to receive said wedges, bevel face plates carried by said 20 shanks, a hub mounted on said shaft, a roller mounted on said hub adapted to engage said plates, and means for operating said hub and sleeve.

11. The combination with a shaft and a 25 fixed wheel mounted thereon, of arms slidably mounted on said wheel carrying segmental rim sections, springs connecting said arms to said wheel, wedges engaging said arms provided with shanks, a sleeve surrounding said wedges, bevel face plates secured to said shanks, a hub loosely mounted on said shaft, a roller mounted on said hub, means for forcing said roller in the path of 30 said plates together with means for forcing said sleeve into engagement with said wedges.

12. The combination with a shaft, of a wheel fixed to said shaft provided with dovetail grooves crossing each other at right angles, arms provided with dovetail heads slidably mounted in said grooves, stops secured in the ends of the grooves, said arms being provided with angle inner ends provided with V-shape tongues, segmental rim sections carried by plates secured to the outer 45 ends of said arms, springs connecting said arms to said wheel, wedges provided with V-shape grooves adapted to receive the

tongues of said arms, said wedges being provided with shanks, a sleeve surrounding said shanks provided with notches adapted to receive said wedges, means for forcing said wedges outwardly in succession, together with means for forcing said sleeve into engagement with said wedges. 50

13. An expandible pulley comprising a wheel adapted to be secured to a shaft having dovetail radial grooves formed in its face, arms provided with dovetail heads mounted in said grooves, the inner ends of said arms 55 being angled and provided with V-shape tongues, segmental rim sections carried by the outer ends of said arms, wedges provided with V-shape grooves in their inclined faces fitting over the tongues of the arms, said wedges being provided with shanks having dovetail tongues at their ends, dovetail grooved plates secured over said dovetail tongues, a sleeve provided with longitudinal grooves arranged on said shanks, said shanks 60 fitting in said grooves, said sleeve being provided with notches to receive said wedges, a hub loosely mounted on the shaft, a roller carried by said hub, and means for throwing said roller in the path of said beveled plates 65 together with means for throwing said sleeve into engagement with said wedges. 70

14. The combination with a wheel, of spring retracted segmental rim sections, wedges for operating said sections provided with shanks, a sleeve arranged over said shanks having an annular groove, a sectional sleeve mounted in said groove provided with pins, a hub mounted on the shaft, a roller carried by said hub, outwardly projecting pins on said hub and forked bifurcated arms 80 engaging with said pins together with means for operating said arms, for the purpose described. 85

In testimony whereof I have signed my name to this specification in the presence of two subscribing witnesses.
